MATTEO TAMBURINI, OF PATERSON, NEW JERSEY.

COMBINATION-LOCK.

1,002,338.

Specification of Letters Patent.

Patented Sept. 5, 1911.

Application filed May 27, 1911. Serial No. 629,944.

To all whom it may concern:

Be it known that I, MATTEO TAMBURINI, a subject of the King of Italy, residing at Paterson, in the county of Passaic and State 5 of New Jersey, have invented certain new and useful Improvements in Combination-Locks, of which the following is a specification.

This invention relates to combination 10 locks and it consists in certain improvements in a combination lock constituting the subject of Letters Patent of the United States, No. 981,140, granted to me January 10th, 1911.

15 One object of the invention is to construct the patented combination mechanism so that it may be used in a practical way to operate not only a bolt but a latch, as well.

20 A further object of the invention is so to construct the parts of the mechanism which directly include the index disks or dials that the same may be concealed except when in use.

25 A still further object is so to construct the parts of the mechanism so as to render it more compact and durable, and facilitate its operation by those familiar with the combination.

30 In the accompanying drawing, Figure 1 shows the improved mechanism in front elevation as mounted in a door; Fig. 2 shows the lock proper and a part of the operating spindle in perspective, the front plate of the lock being removed; Fig. 3 is a vertical 35 sectional view in the longitudinal plane of the axis of the spindle and through that part of the mechanism which includes the index disks or dials; and, Fig. 4 is a sectional view on the line $x-x$ of Fig. 3.

40 In the door a is arranged a lock-casing b of usual construction, the cover not appearing in the drawings. Suitably guided to slide in the lock-casing are a bolt c and a latch d , e being a spring holding the bolt at any position to which it is moved and f a spring 45 normally holding the latch at its outward limit of movement. The bolt has a plurality of notches g in its under side, while the latch has a notch h in one face thereof.

50 i is an auxiliary bolt sliding in the lock-casing b and adapted to be controlled by a removable key j .

The door a has the escutcheons k and l bearing against opposite faces thereof, the escutcheon k having an outwardly

projecting boss m . Fitting this boss is a cylindrical shell n which has an exterior annular shoulder o at its outer end and at its inner end is formed with the threaded projecting stems p which 60 penetrate the escutcheon k , the door a , the lock-casing b , and the escutcheon l and carry at their free ends the nuts q which, when screwed up tight, clamp the shell and the escutcheons securely to the door. In the 65 outer end of the shell n is fixed a head r .

The door a , lock-casing b and shell n , with its head r , afford supporting means for the bolts, latch and springs already named, together with other moving parts, now to be 70 described.

Journaled in the escutcheon l and the head r is a spindle s carrying at its opposite ends the knobs t fixed thereto, the space between the left hand knob in Fig. 1 and the 75 escutcheon l representing the distance which this spindle is longitudinally movable.

The spindle is provided with the wards u and v , said wards being respectively adapted to engage the notched portions of the bolt 80 and latch c and d to move the same. The parts to be actuated (*i. e.*, the bolt and latch) being in the same vertical plane, but the two wards u and v being in different planes crossing the axis of the spindle, it 85 follows that when one of the wards, say u , is operatively engaged with the bolt or latch member, say c , the other ward may rotate without engaging and operating the other member, and vice versa. 90

Arranged side by side in the shell n between the boss m and head r are the rotary index disks or dials w the same and the head r having indices x on their outer peripheries, being penetrated by the spindle 95 s and each having two internal circumferential grooves y connected by a longitudinal groove z . As in my patent referred to, co-acting with these grooves in the dials are studs 2 on the spindle. When the spindle is in its right-hand position in Fig. 1 its ward u is in position to operate the bolt c ; when it is in the left-hand position its ward v is in position to operate the latch d . In 100 the latter position the spindle is in such position that, so far as the ward u and bolt c are concerned, it may be moved longitudinally; it then remains only to move the dials w so that their indices will form the necessary combination with the index on the 105 110

head r to bring their grooves z in alinement with the studs 2.

It will be observed that the shell n is provided with two sight-openings 4. Each of 5 these exposes one, two or more indices on each of the parts r and w . Normally to conceal the indices the shell n carries a sleeve 5 having apertures 6 corresponding to the 10 openings 4 in the shell. When the sleeve 5 is in the position shown in Fig. 4 the indices are exposed. The sleeve 5 is embraced between the escutcheon k and shoulder o .

In order that the escutcheon k may be removed from the shell and spindle after 15 removing the combination mechanism from the door the escutcheon k is provided with the vertical slot 7 through which the wards u and v of the spindle may pass.

Usually, spindle s will stand at the left in 20 Fig. 1 (right-hand knob t engaging head r) and be held normally by the spring-actuated latch so that ward v projects downwardly; the disks w may at that time prevent movement of the spindle to the right by 25 being turned so that their grooves z do not register with the studs 2. The spindle is in this position used to operate the latch.

Upon setting the disks so as to allow movement of the spindle to the right it may be 30 brought to such a position that ward v clears the latch and ward u engages the bolt, whereupon the latter may be shot by turning the spindle. Upon now returning the spindle to its original or left-hand position 35 in Fig. 1 and again disturbing the combination the bolt will be effectually cut off from the influence of the spindle.

In order to hold the disks w against accidental displacement after adjustment, as by 40 rotation of the spindle, I provide a curved detent 8 (Fig. 4) which is pivoted in the opening 4 of the shell and may rest flat against the peripheries of the disks, its toe 45 engaging notches 10 in the disks and the detent being held in that position by turning the sleeve to cover it; by turning the sleeve to uncover the detent the latter may swing out on its pivot (dotted lines, Fig. 4) to release the disks.

Having thus fully described my invention, what I claim as new and desire to secure by Letters Patent is:—

1. The combination, with a suitable supporting means, of a rotary controlling member journaled and having limited movement therein longitudinally of its axis and also having radial wards, a latch and a bolt each movable longitudinally in said supporting means and crossing said member, one ward 55 being engageable with the bolt when said member is in one of its limits of longitudinal movement and the other ward being engageable with the latch when said member is at its other limit of longitudinal 60 movement and means, comprising an indexed rotary part journaled in the supporting means concentric with said member, for holding the latter at either of its limits of longitudinal movement, substantially as described. 70

2. The combination, with a suitable supporting means, of a rotary controlling member journaled and having limited movement therein longitudinally of its axis and also having radial wards, a longitudinally movable spring-actuated latch crossing said member and normally standing in a definite position relatively thereto, said latch having a notch for engagement with one of the wards of said member, a longitudinally movable bolt also crossing said member and notched for the engagement therewith of the other ward of said member, one ward being engageable with the bolt when said member is in one of the limits, and the other ward being engageable with the latch when said member is in the other of the limits, to which said member is longitudinally movable, and means comprising an indexed rotary part journaled in the supporting means concentric with said member, for holding the latter at either of its limits of longitudinal movement, substantially as described. 75

2. The combination, with a suitable supporting means, of a rotary controlling member journaled and having limited movement therein longitudinally of its axis and also having radial wards, a longitudinally movable spring-actuated latch crossing said member and normally standing in a definite position relatively thereto, said latch having a notch for engagement with one of the wards of said member, a longitudinally movable bolt also crossing said member and notched for the engagement therewith of the other ward of said member, one ward being engageable with the bolt when said member is in one of the limits, and the other ward being engageable with the latch when said member is in the other of the limits, to which said member is longitudinally movable, and means comprising an indexed rotary part journaled in the supporting means concentric with said member, for holding the latter at either of its limits of longitudinal movement, substantially as described. 80

3. The combination, with a suitable supporting means, of a part to be actuated movable therein, a rotary controlling member journaled and having limited movement longitudinally of its axis in said supporting means, said member being operatively engageable at one of its limits of longitudinal movement with, and disengaged at the other of its limits of longitudinal movement from, the part to be actuated, a rotary indexed part journaled concentric with said member, said indexed part and said member having coacting means for holding the latter at either of its limits of longitudinal movement, and a detent movable in the supporting means into and out of holding relation to the indexed part, substantially as described. 95

4. The combination, with a suitable supporting means, of a part to be actuated movable therein, a rotary controlling member journaled and having limited movement longitudinally of its axis in said supporting means, said member being operatively engageable at one of its limits of longitudinal movement with, and disengaged at the other of its limits of longitudinal movement from, the part to be actuated, a rotary indexed part journaled concentric with said member, said indexed part and said member having coacting means for holding the latter at either of its limits of longitudinal movement, and a detent movable in the supporting means into and out of holding relation to the indexed part, substantially as described. 100

4. The combination, with a suitable supporting means, of a part to be actuated movable therein, a rotary controlling member journaled and having limited movement longitudinally of its axis in said supporting means, said member being operatively engageable at one of its limits of longitudinal movement with, and disengaged at the other of its limits of longitudinal movement from, the part to be actuated, a rotary indexed part journaled concentric with said member, said indexed part and said member having coacting means for holding the latter at either of its limits of longitudinal movement, and a detent movable in the supporting means into and out of holding relation to the indexed part, substantially as described. 105

4. The combination, with a suitable supporting means, of a part to be actuated movable therein, a rotary controlling member journaled and having limited movement longitudinally of its axis in said supporting means, said member being operatively engageable at one of its limits of longitudinal movement with, and disengaged at the other of its limits of longitudinal movement from, the part to be actuated, a rotary indexed part journaled concentric with said member, said indexed part and said member having coacting means for holding the latter at either of its limits of longitudinal movement, and a detent movable in the supporting means into and out of holding relation to the indexed part, substantially as described. 110

4. The combination, with a suitable supporting means, of a part to be actuated movable therein, a rotary controlling member journaled and having limited movement longitudinally of its axis in said supporting means, said member being operatively engageable at one of its limits of longitudinal movement with, and disengaged at the other of its limits of longitudinal movement from, the part to be actuated, a rotary indexed part journaled concentric with said member, said indexed part and said member having coacting means for holding the latter at either of its limits of longitudinal movement, and a detent movable in the supporting means into and out of holding relation to the indexed part, substantially as described. 115

4. The combination, with a suitable supporting means, of a part to be actuated movable therein, a rotary controlling member journaled and having limited movement longitudinally of its axis in said supporting means, said member being operatively engageable at one of its limits of longitudinal movement with, and disengaged at the other of its limits of longitudinal movement from, the part to be actuated, a rotary indexed part journaled concentric with said member, said indexed part and said member having coacting means for holding the latter at either of its limits of longitudinal movement, and a detent movable in the supporting means into and out of holding relation to the indexed part, substantially as described. 120

4. The combination, with a suitable supporting means, of a part to be actuated movable therein, a rotary controlling member journaled and having limited movement longitudinally of its axis in said supporting means, said member being operatively engageable at one of its limits of longitudinal movement with, and disengaged at the other of its limits of longitudinal movement from, the part to be actuated, a rotary indexed part journaled concentric with said member, said indexed part and said member having coacting means for holding the latter at either of its limits of longitudinal movement, and a detent movable in the supporting means into and out of holding relation to the indexed part, substantially as described. 125

4. The combination, with a suitable supporting means, of a part to be actuated movable therein, a rotary controlling member journaled and having limited movement longitudinally of its axis in said supporting means, said member being operatively engageable at one of its limits of longitudinal movement with, and disengaged at the other of its limits of longitudinal movement from, the part to be actuated, a rotary indexed part journaled concentric with said member, said indexed part and said member having coacting means for holding the latter at either of its limits of longitudinal movement, and a detent movable in the supporting means into and out of holding relation to the indexed part, substantially as described. 130

ble on the shell over its aperture and adapted to hold the detent engaged with the indexed part, substantially as described.

5. The combination, with the door and lock-casing arranged therein, of a cylindrical shell having stems extending from one end thereof and a head in and an annular shoulder around its other end, said stems penetrating the door and holding the shell thereto, a revolute indexed part arranged concentrically in the shell, a rotary controlling member journaled and having limited longitudinal movement in the head and the door, penetrating said indexed part and 10 lock-casing and having a radially projecting ward within the lock-casing, a movable part to be actuated by the ward of said member upon rotating said member when the latter

is at one of its limits of movements, said part to be actuated being arranged in the 20 lock-casing and said indexed part and said member having coacting means for holding the latter at either of its limits of longitudinal movement and the shell having an opening exposing the indices of said indexed part, and a sleeve revolubly arranged on the shell between the door and the shoulder and having an opening adapted to coincide with the opening in the shell, 25 substantially as described. 30

In testimony whereof I affix my signature in presence of two witnesses.

MATTEO TAMBURINI.
